STUD DRIVER

Linton A. Husband, Elmhurst, Ill., assignor to
 General Motors Corporation, Detroit, Mich., a
 corporation of Delaware

Application January 13, 1944, Serial No. 518,069

11 Claims. (Cl. 81—52.5)

This invention is the outcome of efforts to develop a stud driving machine to speed up production, to get better results than can be had by hand operation with a standard torque wrench and to avoid physical fatigue and injuries to the operators.

The objects of the invention are, therefore, to save time in driving studs, to accurately determine the depth of driving, to cause the machine to cease operating if the stud being driven is oversize or undersize, and in other ways to solve the problems associated with driving studs and tightening bolts, screws and nuts.

On the accompanying drawings:

Fig. 1 is a view in elevation of the machine.

Fig. 2 is a similar view on a larger scale of a part of the machine.

Fig. 3 is a view as seen from line 3—3 of Fig. 1.

Fig. 4 is a horizontal section substantially on line 4—4 of Fig. 2.

Fig. 5 is a section on line 5—5 of Fig. 3.

Fig. 6 is a section on line 6—6 of Fig. 3.

Referring by reference characters to the drawings, numeral 11 identifies the base of the machine from which rises a pedestal 13. A table to support the work W is marked 15. It is arranged to be adjusted vertically by any convenient means, the drawings showing adjusting and holding operating members at 17 and 19. Projecting upwardly from pedestal 13 is a post 21 carrying at its upper end a housing 23. The housing is mounted to rotate on the post 21, being limited in its movement by a shouldered collar 25. Slidable horizontally within housing 23 is an arm 27. A suitably mounted stop 29 will serve to limit the movement of the arm in one direction, to the right as shown. Within the housing 23 antifriction rollers 24 may be used to guide the arm.

A guide bar or way 31 is secured to the end of arm 27 for vertically guiding a mounting bracket 33. An air pressure operated motor 35 is mounted on the arms of the bracket 33 for rotation on a vertical axis, antifriction bearings being shown on Fig. 2 at 37.

To move the bracket 33 with the motor vertically on its guideway there is shown a lever 39. It is pivoted to the bracket at 41 and a link 43 connects its work end to arm 27. Downward pressure on the lever 39 moves the motor toward the work W on the table. It does so acting against a spring 45 housed within a tube 47. Tube 47 is secured to the guideway 31 at 49. Within the tube 47 and surrounded by the spring 45 is a post 51 secured at its lower end to the bracket 33. At the upper end of the post is a

washer and nut assembly 53. As the bracket 33 moves downward the spring is compressed by the washer, the lower end of the spring being held by the cap 55 secured to the lower end of the

5 tube 47. On Figs. 1 and 2 is shown at 57 what may be considered to be a stud driver of known construction and which is attached to and adapted to be rotated by the rotor of the motor. In this way the motor threads the stud down into 10 the threaded opening of the work. The stud driver 57 will be of that known type which has a collet to grip the stud when rotated in driving direction and to release the stud when reversely rotated.

15 The operation of the machine is automatic in that it drives the stud to a predetermined depth, whereupon the motor reverses and the stud is left in the work as spring 45 raises the carrier 33 with the motor to its upper limit. It is also automatic 20 in that it accommodates itself to the fit of the threads of the stud in the work. If the stud threads fit properly the engagement of the stud and work threads pulls the carrier 33 to its lower limit whereupon the motor rotation is reversed

25 and the spring 45 pulls the motor and its carrier to the upper limit whereupon the machine action stops as will be explained. It is also automatic in that the machine is stopped if the fit of the stud in the work is too tight or too loose.

30 To effect the above automatic operation for continuing the action with properly fitting stud threads and stopping it in the case of defective studs there is used a torque beam which is bent to an extent commensurate with the torque re-

35 action produced upon the motor casing in response to the varying resistance offered by the work being performed by the rotor. The torque beam is shown on the drawings at 59. It is secured to and extends from the carrier 33 and

40 therefore reciprocates with the carrier and the motor. An arm 61 is secured to and projects from the motor casing in parallelism with the torque beam. Rotation of the motor on its vertical axis resulting from the torque load of driving the stud

45 is transmitted from arm 61 to beam 59 by a connector marked 63. To vary the resistance to rotation offered by the beam 59 provision is made as at 65 for adjusting the connection and to lessen resistance there may be used rollers 67 on the 50 connector for engaging the beam 59. Also any suitable bumper 69 may be used as a stop to engage the beam as it returns to its normal position after being bent therefrom by the rotation of the motor casing.

55 The controlled rotation of the motor casing as

described above is used in the following way to accomplish the automatic operation. A bracket 71 is secured to the motor as best shown by Fig. 4. As the motor casing rotates this bracket 71 rotates. The bracket carries a resiliently controlled push member 73 adapted to operate a switch 75 through intermediate connecting means 76 when the motor has rotated to an extent which corresponds with a given bending of beam 59. It is the purpose of this switch to close an electric circuit by which a lamp bulb, not shown, is illuminated to show the operator that the stud threading is meeting normal resistance. It will be readily seen that this "normal resistance" may be adjusted by moving the connection 63 to a changed position on bar 61. There may be attached to the motor casing a rod 101 (see Fig. 2) extending through a slot 103 in a plate 105. The end of the rod is shown by Fig. 3 as provided with an indicator 107. The motor may be turned with a torque wrench until the indicator 107 reaches the location desired for normal torque and the necessary adjustment then given the connector 63.

If a particular stud being driven is oversize the resistance to driving will cause the motor casing reaction to bend the beam 59 beyond its predetermined normal. The excessive rotation of the motor casing with the bracket 71 causes a spring controlled plunger 77 to actuate another switch marked 79. This switch operates to stop the machine. It has been stated that the motor is of the air pressure operated type. The switch may therefore function in any convenient way to close a valve, not shown, in the pressure line to the motor. After the defective stud has been removed the machine may be again put in operation by a reset button such as 100. On the other hand the fit of the stud may be such that there is some motor casing rotation but less than normal, a condition corresponding to a stud threaded into the work but not with a sufficiently tight fit to properly hold. Again the machine is to be stopped automatically. The following provision is made for this purpose. As shown in Fig. 2 a tubular post 81 is secured to the motor housing and is rotatably supported in the upper bearing of the bracket 33. To this post is secured by adjustable clamping means 82 an arm 83 having an extrusion 85 (Fig. 5). On spring housing 47 which extends in parallel relation to post 81 is adjustably secured a clamp 87. Clamp 87 carries a switch 88. Switch 88 is positioned vertically somewhat below the uppermost position of arm 83. It is designed to be actuated by extension 85 as the motor case reciprocates but only if there is a reaction rotation of the motor casing which is less than enough to actuate the switch 75 indicating normal torque. There is shown on Fig. 5 a roller 90 to be engaged by the extension 85. Fig. 5 shows the relative positions of members 85 and 90 when there is no torque. In the case of normal torque when the arm 83 starts downwardly it at once rotates to an extent sufficient to carry extension 85 beyond the vertical plane of roller 90. Then when the lower limit is reached and the motor starts to rise a no torque condition prevails and the extension again assumes the position shown by Fig. 5 and no contact occurs. If, however, the torque is less than normal the extension 85, as it descends, will engage the switch actuator and stop the machine in the way in which it was stopped by switch 79. The defective stud is removed and the mechanism is again reset. It may happen that so

small a stud is being driven that there is no bending of the torque beam. In this case neither the normal, the excessive or the low torque switches come into operation. The motor merely travels down carrying the stud, reverses and, since there has been no driving torque, the stud comes up with the driver until the upper limit is reached. The defective stud is then removed.

In any of the above cases the action is to be stopped at the upper limit. To that end there is an upper limit switch marked 97 carried by the guideway. It is adapted to be engaged by an actuator marked 98 carried by the bracket. This switch closes the flow of air pressure and the action of the machine ceases.

There will next be described the mechanism for automatically reversing the direction of rotation of the rotor of the motor when the motor reaches the lower limit of its travel. A solenoid controlled valve of well-known form is mounted on the base. It is marked 89. It is designed to direct the flow of compressed air through one or the other of two pipes 95 or 95' to a special valve marked 119 which is attached to and controls the motor 35. When the motor carrier 33 descends to its lower limit an abutment 93 thereon operates a switch 91 to close a circuit through the solenoid controlled valve member 89. This functions to reverse the direction of rotation of the rotor of the motor. The airflow from pipe 95 enters the valve at 109. From pipe 95' it enters the valve at 111. Between points 109 and 111 the valve 119 has a passage marked 113 in which reciprocates a valve rod 123. The rod 123 is operably connected by an arm 127 to a rockshaft 125 so that the shaft rocks in response to the shift from pressure coming from pipe 95 to pressure coming from pipe 95' and vice versa. It may be said that the air pressure motor with reversing means 40 controlled by the equivalent of shaft 125 is not per se a part of this invention. The shaft 125 is flattened as shown at 126 in Fig. 3 and as it turns it causes air under pressure in space 129 to engage on opposite sides of the rotor, not shown, to determine the direction of rotation. The air is admitted to space 129 by way of a passage 121 in the valve, the passage 121 communicating with the two openings 109 and 111 by passages 117 and 120. In each of the two positions of the 45 valve rod 123 it closes one of the passages 117 or 120 as the case may be, air under pressure passing through the other passage. Not only is reversal effected by the lower limit switch but also it is caused by a switch operated by a button 122 at the end of the lever 39. It will be seen therefore that after reversal by the lower limit switch the motor is pulled up to its upper limit by spring 45, where action ceases. For the next stud the operator pulls down on the lever and the still prevailing non-driving relation make possible the proper assembly of the collet of the driver with the stud. The button 122 is then manipulated and the resulting driving rotation then causes the collet to grip the stud and the engagement of the 50 stud in the work pulls down the motor until the rotation is again reversed by the lower limit switch and the spring then pulls the motor to upper limit whereupon the action again stops.

It may be stated that applicant uses a standard air pressure motor, solenoid reversing valve and switches and makes no claim per se for these instrumentalities which he uses on his machine nor for the electrical equipment by which the parts are made to operate. The reversing operation 55 of the air pressure motor is not performed by hand

but by air pressure for which he has designed the special valve marked 119.

It will be seen that the machine can drive the studs to an accurately determined extent, and that it requires only a slight manual effort to withdraw the motor carrier from the upper limit switch, engage the stud and press the button to get forward driving rotation. The rest is automatic. The threaded engagement is such as to pull the motor down against the resistance of spring 45 until the solenoid reversing switch reverses the motor whereupon the collet releases its hold on the stud and the spring pulls the motor and carrier to its upper limit where the upper limit switch stops the operation. If any stud is defective the machine stops permitting its removal.

I claim:

1. In a stud driving machine, a motor, a carrier for said motor mounted to reciprocate, said motor having a reversible rotor, a stud driver carried by said rotor, said motor having a casing rotatably supported in said carrier, said casing rotating in response to the resistance offered by the work of driving a stud into the work, yielding means to resist said casing rotation and switches actuated by said casing rotation and operable to stop the rotation of the rotor in response to degrees of casing rotation corresponding to excessive or too little stud driving torque, first switch means to stop rotation of said rotor in response to a movement of the carrier to a predetermined upper limit and second switch means to reverse its rotation in response to the movement of the carrier to a predetermined lower limit.

2. The invention defined by claim 1, together with lever means to reciprocate said carrier and switch means on said lever means to reverse the rotation of said rotor.

3. The invention defined by claim 1, said motor being of the fluid pressure operated type, a solenoid flow changing valve, said second switch means operable in response to the movement of the carrier to its lower limit to actuate said flow changing valve to cause fluid pressure to take one or the other of two paths and reverse the rotation of the motor.

4. The invention defined by claim 1, said motor being of the fluid pressure type, a motor reversing valve secured to said motor, said valve having a reciprocable valve rod, a rockshaft to reverse the action of the motor, a link connecting said valve rod and rockshaft, and plural connections for fluid to move said valve rod in opposite directions, and said second switch means operable to transmit fluid pressure to said connections selectively.

5. In a stud driving machine, a motor carrier mounted to reciprocate between upper and lower limits, a reversible motor carried by said carrier, a stud driver carried by the rotor of said motor, means to stop rotor rotation in response to the movement of the carrier movement to its upper limit, means to reverse its rotation in response to movement of the carrier to its lower limit, together with means to stop the machine in response to excessive or too little resistance offered by the work.

6. In a stud driving machine, a motor carrier mounted to reciprocate between upper and lower limits, a reversible motor carried by said carrier, a stud driver carried by the rotor of said motor, means to stop rotor rotation in response to the movement of the carrier movement to its upper limit, means to reverse its rotation in response

to movement of the carrier to its lower limit, said motor having a casing journaled for rotation on a vertical axis, torque responsive means to resist the rotation of said casing, together with means to stop the machine in response to excessive torque and also in response to a degree of torque less than a predetermined minimum.

7. In a stud driving machine, a motor carrier mounted to reciprocate between upper and lower limits, a reversible motor carried by said carrier, a stud driver carried by the rotor of said motor, means to stop rotor rotation in response to the movement of the carrier movement to its upper limit, means to reverse its rotation in response to movement of the carrier to its lower limit, said motor having a casing journaled for rotation on a vertical axis, torque responsive means to resist the rotation of said casing, together with means to stop the machine in response to predetermined degree of torque, said torque responsive means being a flexible torque beam secured to said carrier, a rigid rod parallel thereto attached to the motor casing and connecting means therebetween.

8. In a stud driving machine, a motor carrier mounted to reciprocate between upper and lower limits, a reversible motor carried by said carrier, a stud driver carried by the rotor of said motor, means to stop rotor rotation in response to the movement of the carrier movement to its upper limit, means to reverse its rotation in response to movement of the carrier to its lower limit, said motor having a casing journaled for rotation on a vertical axis, torque responsive means to resist the rotation of said casing, together with means

35 to stop the machine in response to predetermined degrees of torque, said torque responsive means being a resilient beam secured to and extending from said carrier, a rigid rod parallel to said beam and secured to said casing, connecting means therebetween, and a plurality of switch contacting means rotatable with said motor casing and adapted to engage and close motor stopping switches in positions of the casing corresponding to excessive bending of said beam and to a bending which is so small as to indicate too little resistance in the work.

9. In a stud driving machine, a motor carrier mounted to reciprocate between upper and lower limits, a reversible motor carried by said carrier, a stud driver carried by the rotor of said motor, means to stop rotor rotation in response to the movement of the carrier movement to its upper limit, means to reverse its rotation in response to movement of the carrier to its lower limit, said motor having a casing journaled for rotation on a vertical axis, torque responsive means to resist the rotation of said casing, together with means to stop the machine in response to predetermined degrees of torque, said torque responsive means

50 being a resilient beam secured to and extending from said carrier, a rigid rod parallel to said beam and secured to said casing, connecting means therebetween, and a plurality of switch contacting means rotatable with said motor casing and adapted to engage and close motor stopping switches in positions of the casing corresponding to excessive bending of said beam and to a bending which is so small as to indicate too little resistance in the work and an additional switch contacting means rotatable with said casing and operable in response to an intermediate bending of the beam to give indication that the resistance offered by the work is normal.

10. In a stud driving machine, a motor carrier mounted to reciprocate between upper and lower

limits, a reversible motor carried by said carrier, a stud driver carried by the rotor of said motor, means to stop rotor rotation in response to the movement of the carrier movement to its upper limit, means to reverse its rotation in response to movement of the carrier to its lower limit, said motor having a casing journaled for rotation on a vertical axis, torque responsive means to resist the rotation of said casing, together with means to stop the machine in response to pre-determined degrees of torque, said torque responsive means being a resilient beam secured to and extending from said carrier, a rigid rod parallel to said beam and secured to said casing, connecting means therebetween, and a plurality of switch contacting means rotatable with said motor casing and adapted to engage and close motor stopping switches in positions of the casing corresponding to excessive bending of said beam and to a bending which is so small as to indicate too little resistance in the work, said switch which is operable in response to too little resistance being fixedly mounted and the switch closing means therefor which rotates with the motor casing being on opposite sides of the vertical plane of said switch in high torque and no torque positions and adapted to render the switch operable

only in a position between the upper and lower positions of the motor casing and in response to a low torque rotary position of said casing.

11. In a stud driving machine, a motor carrier mounted for reciprocation between upper and lower limits, said motor having a rotor to perform work and a casing rotatable in said carrier on a vertical axis, yielding torque resisting means mounted on said carrier, means on the motor casing to variably effect said yielding means in response to variable work loads, a high torque switch mounted on the carrier, a high torque switch closure member carried by the casing, a low torque switch fixedly mounted, a low torque switch closure on the casing adapted to pass or engage said switch as the casing moves vertically dependent upon the resistance offered by the work, a fixed switch adjacent the upper limit of the carrier movement, means mounted on the carrier to actuate said switch to stop the machine, motor reversing means including a switch adjacent the lower limit of carrier travel, means on the carrier to actuate said switch, manual means to reciprocate said carrier and a second reversing switch operating means on said manual means.

LINTON A. HUSBAND.
